UNITED STATES PATENT OFFICE.

CHARLES JONES, OF LONG BEACH, CALIFORNIA.

BASEBALL GAME.

Application filed May 11, 1927. Serial No. 190,426.

My invention is a baseball game in which a mechanical batter is used and the field is laid out in miniature with miniature players represented.

An object of my invention is a game simulating baseball in which a mechanically actuated batter is utilized and a baseball diamond on a small scale is laid out on a suitable surface with miniature figures representing players and pockets to receive the ball.

A further object of my invention is a game simulating baseball in which the people entering the game throw the ball for the mechanical batter to bat. The batter is positioned beside the home plate and the catcher, a miniature permanently fixed figure, is located behind the plate with his gloves directly behind the swinging bat of the batter. The batter swings the bat periodically and an object of the person throwing the ball is to not only throw the ball correctly over the plate but at the proper time to be struck by the bat.

Another object of my invention is the construction of an alley or the like, suitable for amusement parks, in which the walls may be painted to represent part of the grandstand and bleachers of a baseball field, the back wall also representing part of the grandstand. A baseball diamond and field is laid out on an inclined surface sloping towards the persons playing the game. The mechanical batter is preferably actuated by an electric motor to swing the upper part of his body with the bat held in his hands and, after a person throws the ball so that the batter strikes it, the ball may roll down the slope and possibly enter some of the pockets, this being represented by the ball being caught by the miniature player figures.

My invention will be more readily understood from the following description and drawings, in which:

Figure 1 is a perspective view of an alley having my game therein.

Figure 2 is a longitudinal section.

Figure 3 is a perspective view of the mechanical batter.

Figure 3 is another view of the batter, partly broken away, showing the internal manipulating mechanism.

Figure 5 is a transverse section on the line 5-5 of Fig. 4 in the direction of the arrows.

Figure 6 is a horizontal view on the line 6-6 of Fig. 4 in the direction of the arrows.

The layout for the game is illustrated in Figs. 1 and 2 in which the whole structure may be considered as an alley 11, having opposite side walls 12, a rear wall 13, an inclined surface 14, a flat part 15 at the front, a stand 16, and a platform 17 for the players. The rear wall 13 has a painting or the like 18 representing a baseball grandstand and on the side walls there are other paintings representing part of the grandstand and the 60 bleachers, indicated by 19. The dugouts 20 for the players are also indicated in painting. A diamond 21 is laid out on the inclined surface 14 which forms the baseball field. The first, second and third bases are 70 marked by openings 22 and adjacent each of the out-fielders, represented by miniature figures 23, there are other openings 24. There is also an opening 25 adjacent the figure 26 representing the short stop and another 75 opening 27 adjacent the figure 28 representing the pitcher. The batter 29 is a mechanically actuated figure which swings the bat periodically, and directly behind the batter 80 is a miniature figure 30 representing the catcher. The catcher's gloves 31 are directly behind the home plate 32 and are positioned at the same elevation above the horizontal as the path taken by the batter's bat in moving 85 across the plate.

The game is played substantially as follows:

The mechanical batter preferably has an electrical mechanism built in his body structure so that the upper part of his body and arms oscillate periodically whereby the bat held in his hands swings across the home plate from the back towards the front. This mechanical figure is started and stopped in operation by an attendant who may stand 90 on the horizontal surface 15 of the alley. The attendant usually charges the participants in the game a certain amount of money for the privilege of throwing a certain number of balls and would give them prizes or 100 the equivalent if the balls when struck roll into any of the pockets in the baseball field above enumerated. The participants stand on the platform 17 and endeavor to strike the bat as the mechanical batter swings this 105 across the home plate.

The construction of the mechanical batter, designated generally as above by the numeral 29, is substantially as follows:

This batter has a rigid lower body struc- 110

ture 33 with legs 34, the legs being secured rigidly to the floor forming the baseball field and to effect this may have bolts 35 extending upwardly into each leg and bolted through the floor. The lower body structure has a deep recess 36 with cylindrical walls 37. In this recess there is a substantial frame work 38 on which is supported a vertical journal box 39 with a vertical shaft 40 extending upwardly therefrom. A gear 41 is connected to this shaft and is driven by a pinion 42, actuated by a pinion shaft 43. This latter, by means of bevel gears 44, is driven by the motor shaft 45 of the electric motor 46. This motor, as above mentioned, is preferably controlled by a switch which may be located adjacent the stand 16 to be within easy reach of the attendant of the alley.

The upper body structure 47 of the batter 20 has a hollow space 48 with cylindrical walls 49, there being an anti-friction bearing 50 at the meeting edges of the cylindrical walls 37 of the lower body structure and 49 of the upper body structure, with a flange 51 on the outside rigidly secured to the lower body structure. A coiled spring 52 has one end 53 connected to the shaft 40 and the other end 54 connected to the wall of the upper body structure.

30 Rigidly connected to or formed integral with the gear 41 there is a disc 55 having a pin 56 mounted thereon. This pin engages an angular trigger 57 which is pivoted on a bracket 58 on the inside of the wall 49 of the upper body structure. The free end 59 of the trigger is outwardly pressed by a spring 60. A stop lug 61 is mounted on the upper body structure 49 and a cooperating stop lug 62 extends upwardly from the wall 37 of the lower body structure. A positive stop 63 is connected to the lower body structure and extends upwardly in a position to engage the bracket 58 of the trigger mechanism.

45 The batter supports a bat 64 in his hands, the bat preferably being somewhat flexible, and the arms 65 are rigidly connected to the upper body structure. The batter wears a loose shirt 66 which conforms to his shoulders, arms and upper body, and is connected 50 to the breeches 67 which are on the lower body structure and legs. The garments are sufficiently loose so that as the batter's body oscillates in the manner hereunder set forth, the garments twist in accordance with such 55 movement.

The manner of operation of the mechanical batter is substantially as follows:

60 The gear 40 is rotated so that this operates in a clockwise direction, as indicated by the arrow 68, and in such action the pin 56 engages the trigger 57 and, as the spring 60 is quite stiff, the upper part of the body is carried in a clockwise rotation, this swinging the batter and the batter's arms to the rear having relation to the diamond and the partici-

pants. When the stops 61 and 62 on the upper and lower body parts respectively contact, the disc 55 continually rotating causes the compression of the spring 60 and releases the pin 56 from the trigger 57. The action 70 of turning the upper part of the batter's body increases the tension on the spring 52 which is already wound up to a certain extent and on the release of the trigger this spring 52 swings the upper part of the batter's body in an anti-clockwise direction, as indicated by the arrow 69. This action in swinging the bat forward is much more rapid than the slow motion developed by the electric motor in moving the bat to the rear so that, should a participant in the game throw a ball in the correct position to strike the bat and at the proper time, the ball will be given a fair hit. The forward swinging motion of the upper part of the body is stopped by the stop 63 on the lower body part coming in contact with the bracket 58 and holding the upper part of the body structure stationary until the pin 56 again contacts with the trigger 57, whence the operation of oscillating the bat towards the rear is again performed.

80 From the above description, together with the drawings, it will be seen that I have developed a game which closely simulates a baseball game and that each of the participants in the game may play as the pitcher, throwing the ball for the batter to strike. If desired, the stand 16 may be sufficiently close to the batter so that if the ball strikes the bat properly flies may be struck so that participants in the game may endeavor to catch same and if the person pitching catches the fly he may be given an extra present or award by the attendant or manager of the game.

85 Various changes may be made in the principles of my invention without departing from the spirit thereof, as set forth in the description, drawings and claims.

90 I claim:

1. In a baseball game a figure representing 110 a batter, having a fixed lower body part and a rotatable upper body part mounted thereon, the upper part holding a bat, an electric motor mounted in the lower part, a gear driven by said motor, a trigger means interconnecting the gear and the upper part to rotate said upper part in one direction, means to release the trigger after a predetermined movement, and a spring means to return the upper body part to its initial position.

115 2. In a baseball game a figure representing 120 a batter, having a lower body part with a recess therein and having a vertical cylindrical wall, an upper body part holding a bat and having a cylindrical wall, with antifriction 125 bearings between said walls, an electric motor mounted in the lower part, a shaft rotatably mounted in the lower part, a gear connected to said shaft, means to rotate said gear from the motor, a trigger on the upper body 130

part, means interconnecting the trigger and the gear, a spring on the shaft interconnecting the shaft and the upper body part, means to release the trigger after a predetermined 5 rotation in one direction, and a spring returning the upper body part to its initial position.

3. In a baseball game a figure representing a batter having a fixed lower body part, an upper rotatable body part mounted thereon 10 holding a bat, a vertical shaft journaled in the lower part, a gear on said shaft, an electric motor to operate said gear, a pin connected to the gear, a trigger on the upper part to engage said pin, interengaging stops on the upper 15 and lower parts to limit the rotation of the upper part relative to the lower part, a spring operating on the trigger, said spring being actuated to release the trigger from the pin, and a second spring actuating the upper 20 part of the body structure to rotate same in a reverse direction.

4. In a baseball game a figure representing

a batter, having a fixed lower body part with a recess therein and cylindrical walls, an upper body part holding a bat and having a recess with a downwardly extending cylindrical wall, the said walls engaging with an anti-friction bearing, a frame in the lower body part having a shaft journaled therein, an electric motor to rotate said shaft, a pin, means connecting said pin to the shaft, a trigger mounted on the upper part to engage the pin, interengaging stops on the upper and lower parts, the said trigger having a spring to release the trigger from the pin on engagement of said stops, a spring interconnecting the shaft and the upper body part to swing said part in an opposite direction on release of the trigger, and a stop in the lower body part to limit the reverse swinging movement 40 of the upper part.

In testimony whereof I have signed my name to this specification.

CHARLES JONES.
